UNITED STATES PATENT OFFICE.

ADAM MARKGRAF, OF EDEN, PENNSYLVANIA, ASSIGNOR TO THE EDEN MANUFACTURING COMPANY, OF SAME PLACE.

DESIGN FOR A CURTAIN OR PORTIÈRE.

SPECIFICATION forming part of Design No. 20,637, dated March 24, 1891.

Application filed February 16, 1891. Serial No. 381,705. Term of patent 3½ years.

To all whom it may concern:

Be it known that I, ADAM MARKGRAF, a citizen of the United States, and a resident of Eden, Bucks county, Pennsylvania, have invented a new and original Design for a Curtain or Portière, of which the following is a specification.

My design for a curtain or portière is fully shown in the accompanying drawing.

10 The design comprises the mottled groundwork *a*, plain transverse stripes *b*, and patterned transverse stripes *d*, *f*, and *g*. The top portion of the curtain overhangs, and both on said overhanging portion of the curtain and 15 on the bottom of the same is a pendent fringe *h*.

The particular design of the patterned stripes is immaterial, the essential features of the design being the mottled groundwork and the transverse stripes, some of which are plain and some patterned.

I claim—

The design for a curtain or portière, substantially as described, and as shown in the accompanying drawing.

In testimony whereof I have signed my name to this specification in the presence of two subscribing witnesses.

25 ADAM MARKGRAF.
